UNITED STATES PATENT OFFICE

JAMES I. HOLCOMB, OF INDIANAPOLIS, INDIANA, ASSIGNOR TO HOLCOMB AND HOKE MANUFACTURING COMPANY, OF INDIANAPOLIS, INDIANA, A CORPORATION

DESIGN FOR A CABINET FOR A POP CORN MACHINE

Application filed September 19, 1931. Serial No. 41,157. Term of patent 3½ years.

To all whom it may concern:

Be it known that I, JAMES I. HOLCOMB, a citizen of the United States, residing at Indianapolis, in the county of Marion and State of Indiana, have invented a new, original, and ornamental Design for a Cabinet for a Pop Corn Machine, of which the following is a specification, reference being had to the accompanying drawings, forming part thereof.

Figure 1 is a front perspective view of a cabinet for a pop corn machine showing my new design. Figure 2 is a rear perspective view of the same on a reduced scale.

I claim:

The ornamental design for a cabinet for a pop corn machine, as shown.

JAMES I. HOLCOMB.
